MICROMANIFOLD FOR POWDER CLOUD DEVELOPMENT

Paul G. Andrus and Lewis E. Walkup, Columbus, Ohio, assignors, by mesne assignments, to Haloid Xerox Inc., Rochester, N. Y., a corporation of New York

Application November 3, 1954, Serial No. 466,576

3 Claims. (Cl. 118—637)

This invention relates in general to xerography and in particular to the development of xerographic images.

In the art of xerography an electrostatic latent image is formed on an insulating surface, such as, for example, a photoconductive insulating surface, by the combined action of an electric field applied through a photoconductive material and action of light or suitable activating radiation on the photoconductive material to cause selective conductivity in accordance with the pattern of radiation to which the material is exposed. The result of this combined exposure and field is a pattern of electric charge known to the art as an electrostatic latent image which is capable of utilization, for example, by deposition thereon of finely divided material, such deposition being known in the art as development.

It has been found by others in the art of xerography that an electrostatic latent image can be developed very satisfactorily by presenting to the image surface a cloud of charged powder particles with a conductive surface or development electrode positioned very closely adjacent to the image surface, preferably at a distance therefrom in the order of about $\frac{1}{40}$ to $\frac{1}{100}$ of an inch or in some instances even somewhat closer than $\frac{1}{100}$ inch. It has also been found by others in the art of xerography that one effective way of preparing a cloud of substantially uniformly charged particles is to form a powder cloud in a suitable cloud generator and pass the cloud under conditions of turbulence through a restricted opening, such as, for example, a capillary tube.

In xerographic development according to these methods there are many inherent problems caused, among other things, by the need for working in an extremely confined space and with extremely fine tolerances, this need being brought about by the narrow space between the image surface and the development electrode. For example, the usual development of a xerographic image involves uniform deposition of powder particles or other finely divided particulate material, across an area of normal picture size which may, for example, be an area whose smallest dimension is several inches or an area whose smallest dimension is a foot or more. The introduction of a cloud uniformly across this entire area in a development space in the order of $\frac{1}{40}$ to $\frac{1}{100}$ inch thick has obviously presented many serious problems. The other somewhat related problem is the fact that powder tends to deposit from the cloud on all available surfaces, including not only the image surface, but the surfaces of other members through which it passes, and such deposition results in irregular operation of the developing mechanisms. It is, therefore, desirable to pass the powder cloud through its turbulent zone immediately prior to introduction into the actual development space and to introduce the powder cloud to the development space simultaneously at a plurality of locations in order to reduce to a minimum the impairment of results.

It is, accordingly, an accomplished object of the invention to provide new and improved development ap-

paratus for xerographic images wherein a uniform cloud of particles is introduced simultaneously at a plurality of locations into an extremely fine development space between a xerographic image bearing surface and a closely adjacent development electrode.

It is another object of the invention to provide new development means, methods and apparatus for the deposition of charged powder particles from a gas suspension onto an electric image.

It is still another object of the invention to provide in xerographic development apparatus means, methods and apparatus for simultaneously presenting to an extremely narrow development space at a plurality of locations, a freshly charged and deagglomerated cloud of powder particles and it is a related object of the invention to provide a new manifold for charging and deagglomerating such particles directly into an extremely narrow development space.

Additional objects of the invention will in part be obvious and will in part become apparent from the following specification and drawings in which:

Fig. 1 is an enlarged diagrammatic view in cross section of a portion of development apparatus in accordance with one embodiment of the invention;

Fig. 2 is an enlarged view partially in section of a micromanifold in accordance with one embodiment of this invention;

Fig. 3 is a schematic flow diagram illustrating the apparatus and process of one form of the present invention;

Fig. 4 is a diagrammatic view of development apparatus according to another embodiment of the invention;

Fig. 5 is a bottom cross section of a portion of the device shown in Fig. 4;

Fig. 6 is a front view of the exit end of the development zone structure of the apparatus shown in Fig. 4.

Referring to the figures, there is shown in Fig. 1 a cross section of a portion of development apparatus according to one embodiment of the invention. In this apparatus a xerographic plate 11 is suitably positioned in a device for development of the xerographic image. Desirably, as shown, the xerographic plate is placed face down in the development position so that only electrical forces rather than forces of gravity will cause deposition of powder material thereon. Directly below the xerographic plate is a development electrode 12 spaced at an extremely close spacial relationship with respect to the xerographic plate by means of a plurality of spacers 13.

In the preferred operation of the invention, the surface of the xerographic plate 11 and the surface of the development electrode 12 are placed as close together as possible with respect to ordinary machining practice and skill so that the two surfaces are relatively uniformly spaced apart over their entire area to permit the free flow therebetween of a cloud of finely divided particles. It has been found in practice that desirable spacing is in the order of about $\frac{1}{40}$ inch since this spacing is relatively close and yet is within the realm of good manufacturing practice for the good presentation of surfaces substantially parallel with one another and substantially uniformly spaced across the entire area.

It has further been found in practice that to achieve significant results this spacing must be less than about $\frac{1}{8}$ inch, preferably about $\frac{1}{40}$ inch or closer, and may be as narrow as a minimum spacing which will permit the passage of the cloud of powder particles between the two surfaces without channelling or irregularity in flow caused by irregularities of the surfaces.

Leading into the space between the xerographic plate 11 and the development electrode 12 is a conduit 14 operably connected to a source of powder cloud and adapted

70

and positioned to feed the powder cloud into this development space. Desirably, the other end of the conduit is connected to a suitable powder cloud generator as illustrated hereinafter.

The xerographic plate 11 according to this form of the invention is a metallic or like conductive member having a substantially flat and smooth surface with a photosensitive layer 15 coating the surface. Desirably, according to usual practice, borders and the like around the photosensitive layer may be bare and electrically conductive. According to present commercial practices, the photosensitive layer 15 is a coating of vitreous appearing selenium which has been deposited on the metallic surface under carefully controlled conditions to form a mirror-smooth selenium surface characterized by being a photoconductive insulator and generally having a thickness between about 0.0005 and 0.01 inch. It is to be understood, however, that insulating surfaces in general, on which an electrostatic image exists, may be appropriately employed for development.

Suitably positioned adjacent to the active development area and desirably in the uncoated border at one end or side of the xerographic plate is a micromanifold 20 illustrated in greater detail in Fig. 2. This micromanifold is a very thin block of solid material having a plurality of holes, capillaries or tubes 21 extending therethrough. The thickness of this block or micromanifold is designed and constructed to be the same as the spacing between the xerographic plate 11 and the development electrode 12. Thus, for example, if these two surfaces are to be spaced apart by $\frac{1}{40}$ inch, then the micromanifold likewise is $\frac{1}{40}$ inch thick. In illustration, one form of micromanifold 20 which has been constructed and operated was 1 inch long and contained 30 ducts, each 0.0035 inch and spaced 0.031 inch apart; the micromanifold width, and therefore, the duct length was 0.1 inch and the thickness was 0.025 inch, this thickness likewise being the spacing between the xerographic plate and the developed electrode. The micromanifold with these dimensions was suitably employed for the development of a xerographic image on a xerographic plate having a size of 1 inch by 5 inches of sensitive area, the micromanifold being placed adjacent to the shorter edge of the plate. The plate consisted of a conductive or metal backing member having a layer of vitreous selenium of about 0.002 inch thick on its surface whereby the spacing between the surface of the selenium and the development electrode was about 0.023 inch.

It is apparent that the manufacture of a micromanifold of these dimensions containing holes of the desired thickness passing edgewise through a relatively thin body is a critical manufacturing operation. One particularly valuable and easy way of producing a structure of the desired critical dimensions and specifications is as follows. Two accurately machined strips of brass, each 1 inch long, $\frac{1}{10}$ inch wide and $\frac{1}{100}$ inch thick were prepared and a grid was prepared with 32 wires to the inch, the wires having a diameter of 0.0035 inch. The two strips of brass were placed on either side of this grid under a force of about 20,000 pounds and in this position were carefully soldered together. The wires then were pulled out from between the brass strips leaving ducts of like diameter in the solder between the brass.

The dimensions of the micromanifold may be adjusted or varied as desired, keeping in mind the need to maintain a minimum thickness so as to achieve minimum spacing between the xerographic plate and the development electrode, and keeping in mind the need for having a plurality of very fine ducts passing edgewise through the manifold. For the development of extremely large size pictures it is desirable to employ a substantially longer manifold having a plurality of ducts at least some of which are positioned near the ends and others desirably near the center of the micromanifold. Preferably, the

micromanifold is of substantially equal length with respect to the width of the surface being developed, and the ducts are generally uniformly spaced along the length of the manifold. It is now believed that superior results are achieved in this invention with the ducts so close together that the gas from the ducts merges into a unitary stream before the gas reaches laminar flow.

Referring to Fig. 3 the operation of the invention may be more readily determined. In this embodiment of the invention a xerographic plate 11 having a photosensitive layer 15 on one surface thereof is placed closely adjacent to a development electrode 12, optionally mounted within a development cabinet 23. A filter 24 at one end of the development cabinet permits discharge of air from the cabinet with retention of the developer material or finely divided particulate material which is to be deposited on the xerographic image. Desirably, means are provided for applying an electric potential difference between the backing member of the xerographic plate 11 and the development electrode 12. These means may include, for example, a battery 22 or similar D. C. power source connected through a potentiometer 25 to one or the other of the xerographic plate or the development electrode. The xerographic plate 11 and development electrode 12 are suitably spaced apart by means of spacer 13 and micromanifold 20 which are placed between the two surfaces. The micromanifold is located and positioned to feed directly into the development space between the development electrode 12 and the photosensitive coating 15 of the xerographic plate.

On the opposite side of the micromanifold away from the development space a tube or conduit 14 leads from a cloud generator 26 to the development electrode and into the space behind the micromanifold. A suitable air or gas supply source 27 is adapted to feed through conduit 28 into the cloud generator to cause formation of a cloud of suspended powder or other particulate material which is then led through the micromanifold and into the development zone.

In operation a xerographic plate is suitably charged, for example, by spraying ions thereon from a corona discharge electrode and is exposed to a pattern of activating radiation which is to be recorded, thus forming an electrostatic latent image on the xerographic plate. The plate is then placed in position over the development electrode, as illustrated in Fig. 3. The air or gas supply source 27 is energized forcing compressed air or gas through the cloud generator to produce a suspension of developer particles in air, and this cloud suspension is passed under turbulent conditions through the duct 21 in micromanifold 20, emerging therefrom in a charged and deagglomerated state into the development space adjacent to the image bearing surface 15. The bias or potential on the xerographic plate or development electrode is set as desired and the finely divided particles are deposited in configuration in accordance with the electrostatic latent image, thus forming a developed xerographic picture.

In the present specification, the term "micromanifold" is used to relate to a block or body of solid material having passing therethrough a plurality of capillary ducts of extremely fine diameter. These ducts are as fine as is consistent with the turbulent flow therethrough of a cloud of powder particles and are designed to produce a high degree of turbulence with a minimum of danger of plugging or blocking of the ducts. It is intended that the micromanifold be used with a finely divided powder having particles generally in the size range of about 1 or several microns and less frequently with the average particle size being a small fraction of 1 micron. The duct diameter desirably should be less than 0.020 inch in order to achieve turbulent flow at reasonable flow rates and preferably is in the order of less than 0.005 inch with an optimum duct diameter believed to be about 0.002 to 0.003 inch. Relatively wide variation is permissible in the length of the duct and it is believed that a duct length

of as much as 1 inch is operable. However, operation at reasonable air pressures and reasonable rates of air flow make somewhat shorter ducts desirable and a duct length of 0.1 inch has been found to be eminently satisfactory as well as easier to construct, and for practicable air pressures a duct length of up to $\frac{1}{2}$ inch is believed to be the maximum. The micromanifold should be as long and should have as many ducts as is found desirable according to best operational and manufacturing practice, the ducts preferably being less than $\frac{1}{8}$ inch apart.

In forming the cloud suspension it is desirable to use air or other gas which can conveniently be passed through the system to form the powder cloud and to permit charging thereof. In addition to ordinary compressed air, it has been found particularly convenient to employ a pre-formed cartridge containing a gas such as Freon 12 which is believed to be a normally gaseous fluorine substituted hydrocarbon, the cartridge containing this gas at a pressure of at least 50 p. s. i. With the use of Freon 12 and a finely powdered charcoal, excellent xerographic images have been developed. As far as can be determined, other gases under pressure are likewise equally satisfactory.

The desired rates of flow can readily be determined by those skilled in the art. The following conditions, however, have been employed with satisfactory results with Freon 12 as the suspending gas. To insure turbulent flow through the small capillary tubes of the micro-manifold a Reynolds number of 8,000 was selected for the flow. By mathematical calculation, it was determined that the Reynolds number should equal to approximately 330 times the flow rate in liters per minute divided by the diameter of the duct in inches, thus calling for the flow rate of 0.085 liter per minute in the device specifically described. In continuing the mathematical calculations, several arbitrary rules of thumb can be used to gain additional information about the size and construction of the manifold. For example, in the development of a 20 square inch picture, such as a 4 x 5 picture area, it has in the past been found desirable to employ a gas flow of about 12 liters of gas per minute. It is apparent, therefore, that for a flow of 0.085 liter per minute through each duct that the development of a 20 square inch picture under comparable conditions calls for about 140 ducts across a 4 inch width, or about 35 ducts per inch for optimum operation. Similarly, based on this same figure of 0.085 liter per minute and taking an arbitrarily assumed gas pressure of 60 p. s. i., it can be determined mathematically that an optimum limit for practical operation calls for a duct length of not over about $\frac{1}{2}$ inch. Since a gas pressure of about 60 p. s. i. is readily obtained and is a convenient basis of operation there follows directly a preferred limit of duct lengths of not over about $\frac{1}{2}$ inch when operating under these conditions although increased pressure permits a corresponding increase in duct lengths. It is understood that similar determinations can be made with respect to air and other gases as well as for the Freons.

Referring to Figs. 4, 5 and 6 there is illustrated semi-diagrammatically a further embodiment of the invention. According to this embodiment, developing mechanism is housed in a suitable cabinet 40 preferably having a door 41 secured to the walls of the cabinet by suitable hinges 42 or the like for convenient access into the interior of the cabinet. Mounted within the cabinet is a development electrode 44 having a plurality of spacers 45 optionally at the exit end thereof. Positioned on the development electrode at the entrance end is a micromanifold 20 desirably extending across the width of the development electrode. Preferably shoulders or runners 46 extend upwardly along the sides of the development electrode to serve as side supports and dust seals between the development electrode and a xerographic plate placed thereon.

A xerographic plate 11 is adapted to be placed on the development electrode supported by the shoulders, 75

spacers and manifold so as to form a development space between the electrode and the plate. As thus formed, the development space is a long, extremely narrow, flat chamber extending between the plate and the development electrode having its entrance portion at the manifold 20 and having its exit portion between spacers 45 at the opposite end of the plate. The sides are sealed against escaping gas or dust by shoulders 46.

Also mounted within cabinet 40 is an air or gas supply 10 48 from which a tube or conduit 49 leads through control valve 50 to a slit-like nozzle or series of nozzles 51. This slit-like nozzle is adapted and directed to feed a jet of air directly toward the ducts in manifold 20. If feasible, the jet of air from the jet or series of jets covers the entire length of this manifold. Mounted to pass between the nozzle 51 and the manifold 20 is a power impregnated ribbon 52 desirably passing through ribbon guides 53. The ribbon preferably is carried on a feed reel 54 and is adapted to be passed between the nozzle 51 and the manifold to a take-up reel 55 which preferably is spring or motor driven in order to move the ribbon at a controlled rate. In practice, the nozzle 51 and manifold 20 are relatively close together, thereby the ribbon 52 will pass almost in direct contact with the manifold. 15 20 25 Thus, a jet of gas from the jet 51 strikes against the ribbon 52 and carries a supply of powder in gas suspension through the manifold into the development zone and out from the opposite end thereof. A filter 57 is positioned in the adjacent wall of the cabinet 40 to permit 30 exit passage of the gas while collecting any powder particles that are not deposited in the development zone or elsewhere in the cabinet.

In use and operation a xerographic plate which has been properly charged and exposed to form an electrostatic latent image thereon, is placed in position on the manifold 20 and spacers 45 and the gas supply and ribbon are activated. Desirably valve 50 is controlled or controllable from outside the cabinet as also is the drive mechanism for reel 55. As these two mechanisms, 35 40 the valve and the ribbon drive, are activated, a stream of powder bearing gas is passed under turbulent conditions through the manifold 20 whereby the powder particles are substantially uniformly charged and are substantially deagglomerated. Passing from the micro-manifold, these particles thereupon are deposited on the xerographic plate in conformity with the electrostatic latent image. After development is complete, the mechanism is stopped and the developed plate may be removed for other utilization as desired.

45 It is apparent that the invention is adapted to operate with any suitable source of powder cloud generator, but as is shown in Figs. 4 to 6, a ribbon generator is peculiarly suited to the manifold disclosed herein, and one embodiment of the invention specifically contemplates the combination, as disclosed, of manifold and powder impregnated ribbon. In such case, a cloth ribbon or the like is preloaded with a finely divided powder material such as a pigmented resin, colored powder, charcoal or the like, and the ribbon is then placed in the development 50 55 apparatus as illustrated.

60 It will be understood that numerous variations and modifications may be made within the scope of the invention and that the invention is to be limited only by the appended claims.

65 What is claimed is:

1. Apparatus for developing an electrostatic image on an electrically insulating layer comprising in combination an electrically conductive development electrode having a surface conforming to the shape of said layer, means to support said layer in opposite, spaced, substantially parallel relation above said development electrode to provide a development zone between said electrode and said layer, a strip-like block positioned at one end of the development electrode and extending substantially completely across one edge of the development zone, a

multiplicity of fine ducts positioned along the length of said block and extending through the block from the development zone, the diameter of the ducts being less than 0.020-inch, means for generating and flowing a gas suspension of finely-divided development material from said generating means sequentially through said ducts and the development zone, the restricted diameter of the ducts producing turbulent flow in the powder cloud serving to simultaneously deagglomerate the development material and electrically charge the material through triboelectric contact with the walls of said ducts.

2. Apparatus for developing an electrostatic image on an electrically insulating layer comprising in combination an electrically conductive development electrode having a surface conforming to the shape of said layer, means to support said layer in opposite, spaced, substantially parallel relation above said development electrode at a distance of no more than $\frac{1}{8}$ -inch to provide a development zone between said electrode and said layer, a strip-like block positioned at one end of the development electrode and extending substantially completely across one edge of the development zone, a multiplicity of fine ducts positioned along the length of said block and extending through the block from the development zone, the diameter of the ducts being less than 0.020-inch, means for generating and flowing a gas suspension of finely-divided development material from said generating means sequentially through said ducts and the development zone, the restricted diameter of the ducts producing turbulent flow in the powder cloud serving to simultaneously deagglomerate the development material and electrically charge the material through triboelectric contact with the walls of said duct.

3. Apparatus for developing an electrostatic image on an electrically insulating layer comprising in combina-

tion an electrically conductive development electrode having a surface conforming to the shape of said layer, means to support said layer in opposite, spaced, substantially parallel relation above said development electrode at a distance of no more than $\frac{1}{40}$ -inch to provide a development zone between said electrode and said layer, a strip-like block positioned at one end of the development electrode and extending substantially completely across one edge of the development zone, a multiplicity of fine ducts positioned along the length of said block and extending through the block from the development zone, the diameter of the ducts being about 0.002 to 0.003-inch, means for generating and flowing a gas suspension of finely-divided development material from said generating means sequentially through said ducts and the development zone, the restricted diameter of the ducts producing turbulent flow in the powder cloud serving to simultaneously deagglomerate the development material and electrically charge the material through triboelectric contact with the walls of said duct.
